UNITED STATES PATENT OFFICE

2,188,630

INTERNAL COMBUSTION ENGINE

Frederick P. Graham, Port Orange, Fla.

Application October 18, 1937, Serial No. 169,734

1 Claim. (Cl. 123—58)

This invention relates to a compound drive detonating engine and more particularly to an engine construction which will possess simplicity in construction, maximum efficiency, flexibility, compactness for power development and may be manufactured and maintained in operation at a minimum cost.

Another object of this invention is the provision of a drive, consisting chiefly of a main or ring gear mounted rigidly on a main or power shaft and in mesh with a plurality of pinions operatively connected with pistons of power cylinders, whereby a maximum number of power cylinders may be compactly arranged or grouped and permitting long strokes for the pistons of the power cylinders, resulting in greater power development and making it possible for a complete piston power cycle on the four cycle principle of operation to each revolution of the main shaft or two complete power cycles on the two cycle principle of operation to each revolution of the main shaft.

Another object of this invention is the provision of an engine of the above stated character wherein compactness and accessibility of various parts will be paramount by having the power cylinders grouped in pairs with a single head for each pair of cylinders and includes a detonating cylinder, the detonating cylinder supplying burning fuel to the pairs of power cylinders for the ignition of the fuel therein and the detonating cylinders being supplied with fuel from the power cylinders during the compressing of fuel therein.

With these and other objects in view, this invention consists in certain novel features of construction, combination and arrangement of parts to be hereinafter more fully described and claimed.

For a complete understanding of my invention, reference is to be had to the following description and accompanying drawings, in which:

Figure 1 is a vertical sectional view taken on the line 1—1 of Figure 2 and illustrating a compound drive detonating engine constructed in accordance with my invention.

Figure 2 is a transverse sectional view taken on the line 2—2 of Figure 1.

Figure 3 is a transverse sectional view taken on the line 3—3 of Figure 1.

Figure 4 is a transverse sectional view taken on the line 4—4 of Figure 1.

Figure 5 is a transverse sectional view taken on the line 5—5 of Figure 1.

Figure 6 is a sectional view taken on the line 6—6 of Figure 4.

Figure 7 is a fragmentary sectional view illus-

trating one of the power cylinders and its piston.

Figure 8 is a fragmentary sectional view taken on the line 8—8 of Figure 2.

Figure 9 is a fragmentary sectional view taken on the line 9—9 of Figure 2.

Figure 10 is a fragmentary sectional view illustrating fuel ports between a pair of power cylinders and an intake manifold and showing a check valve therein.

Figure 11 is a diagrammatical view showing 10 the relative position of the piston during the two cycle operation of this engine.

Figure 12 is a fragmentary sectional view showing a modification of this invention.

Referring in detail to the drawings, the numeral 1 indicates a center housing for enclosing a compound drive which includes a cylinder 3 and end walls 4 and 5 joined together by tubes 6 through which tie bolts 7 extend. Supported on the end walls 4 and 5 are power cylinders 8 grouped in pairs and each pair provided with a head 9. Head plates 10 engage the heads 9 and have the tie bolts 7 extending therethrough so that the heads and head plates as well as the power cylinders will be kept assembled on the center housing 1. The head plates 10 and end plates 4 and 5 have aligned bearings to rotatably support a hollow power takeoff shaft 12. The bearings carried by the end plates 4 and 5 include stuffing boxes 13 of the adjustable 15 type to engage with the power takeoff shaft. The bearing of the end plate 5 receives a hub 14 of a ring gear 15, the latter being suitably secured on the power shaft. The bearing of the end plate 4 is of sectional construction to 20 rotatably support hubs 16 of gears 17 which mesh with the ring gear and on which are formed 25 wrist pins 18. The wrist pins are engaged by cross heads 19 and each cross head has pairs of connecting rods 20 secured thereto which are in 30 turn connected to pairs of pistons 21 operable 35 in the pairs of power cylinders 8. In this arrangement of power cylinders and pistons each cross head has two pairs of pistons connected thereto with the pairs of pistons in opposed relation, as clearly shown in Figure 6. The bearings 40 for the power shaft are of the antifriction type.

The pistons 21 are adjustably and detachably connected to the connecting rods 20. The adjustability of the pistons permits various compression ratios to be obtained in the power cylinders. The pistons 21 and the heads cooperate in forming in the power cylinders firing chambers. The pistons have fuel ports 22 in which 55

are located spring seated check valves 23. The end plates 4 and 5 of the housing 1 carry an intake manifold 24 which communicates with the power cylinders 8 by ports 25 having spring seated check valves 26 therein. Each port 25 supplies a pair of power cylinders with fuel, as shown in Figure 10, between the skirt ends of the pistons and the end walls 4 and 5, the latter being provided with stuffing boxes 27 to receive the connecting rod so that fuel drawn into the power cylinders between the skirt ends of the pistons and the end walls 4 and 5 of the housing will be compressed during a portion of the power strokes of the pistons. It is to be understood that this engine operates on the two cycle principle and after the pistons have completed substantially their power strokes the pressure of the fresh fuel in the power cylinders between the skirt ends of the pistons and the end walls 4 and 5 will unseat the valves 23 and permit said fuel to enter the firing chambers of the power cylinder. During the initial movement of the fresh fuel into the firing chambers, the exhaust valves 28 of the power cylinders are open to permit spent gases in the firing chambers to escape. The exhaust valves 28 are closed during the compression and major portions of the power strokes of the pistons. It is to be understood that any type of carburetor is connected to the intake manifold 24 for the purpose of supplying a low grade of fuel to the power cylinders.

Cam plates 29 are secured on the power takeoff shaft 12 and include cam ribs 30 and 31. The exhaust valves are grouped in pairs and are engaged by rocker arms 32 pivotally mounted, as shown at 33. The rocker arms engage the cam ribs 31. The construction of the cam ribs 31 is such as to time the movement of the exhaust valves to exhaust spent gases from the firing chambers of the power cylinders when the latter begin to receive fresh gases from the intake manifold through the ports of the pistons.

Each cylinder head 9 carries a detonator cylinder 34 connected to the firing chambers of the pair of power cylinders of said head by fuel passages 35 and operable in the detonator cylinder is a detonating piston 36 spring pressed by a spring 37. The detonator pistons engage with rocker arms 37 which are pivotally mounted, as shown at 38. The rocker arms 37 are operated by the cam ribs 39. The cam ribs are of such a construction that rapid movement will be imparted to the detonating pistons as the power pistons reach the limit of their compression strokes for the purpose of igniting fuel in the detonator cylinders by compression so that the burning fuel of the detonator cylinders may pass into the firing chambers of the power cylinders and ignite the compressed fuel therein driving the power pistons on their power stroke. It is to be understood that the detonator cylinders are supplied with fuel from the firing chambers of the power cylinders during the compression strokes of the pistons. The detonator pistons advancing rapidly on their compression stroke bring about spontaneous combustion of the fuel in the detonator cylinders and the burning fuel is driven from the detonator cylinders by the detonating pistons thereby eliminating necessity of scavenging the detonator cylinder by some means other than the detonating piston.

In the construction of the engine described, the power pistons of each pair of power cylinders move in unison and on the same cycle of operation

and when a pair of pistons of a pair of power cylinders is on its power stroke the pair of pistons of the opposed pair of power cylinders will be on its compression stroke.

As the cycle of operation occurring in each pair of power cylinders is the same, in describing the operation of the engine only a pair of power cylinders will be referred to.

In operation, the power pistons of a pair of power cylinders moving in the direction of the head of said pair of power cylinders draws fuel into the power cylinders between the end plates of the housing and the skirts of the pistons and on a reverse movement of the power pistons the fuel will be compressed until the pressure is sufficient to open the check valves 23 and the compressed fuel passes into the firing chambers by way of the ports 22. The pistons moving towards the head further compresses the fuel in the firing chambers and also in the detonating cylinders and as the power pistons complete their compression stroke the detonator piston moves rapidly bringing about spontaneous combustion of the fuel in the detonator cylinder and this burning fuel reenters the firing chambers of the firing cylinders and ignites the fuel therein to drive the power pistons on their power stroke and as the power pistons substantially complete their power strokes the fresh fuel forces open the check valve 23 and at the same time the exhaust valves are opened so that the incoming fresh fuel under compression will drive the spent gases outwardly to the atmosphere by way of the exhaust valves. As soon as the power pistons have completed their power stroke and start on their compression stroke the exhaust valves close.

The engine shown and described in detail in this application permits a maximum amount of horse power to be developed with the use of a low grade of fuel with the overall dimension of the engine reduced to a minimum. While the engine has been shown and described as employing detonators for igniting the fuel, electrical ignition may be substituted for said detonators through a rearrangement of some minor parts of the engine. Also the type of drive described may be readily adapted to engines operating on any kind of explosive fuel and on the ordinary Diesel principle or on the type employing electrical ignition.

The compression ratio employed within the power cylinders will be well below the detonation of the fuel while the compression ratio in the detonator cylinders will be high and sufficient to assure spontaneous combustion of the fuel therein so that the burning fuel of the detonator cylinders can ignite the low compressed fuel in the power cylinders. Each pair of power cylinders having the compressed fuel therein ignited from the burning gases form a single detonator cylinder which materially increases the compactness and efficiency of the herein described type of engine.

Instead of employing the cross heads 19 a construction may be used, as shown in Figure 12, wherein the opposed pairs of pistons are shown with connecting rods 40 pivoted thereto and to a journal 41 mounted for rotation on the pin 18 of the gear 17.

When the structure as shown in Figure 12 is employed the engine will operate on a four cycle principle.

What is claimed is:

In an engine of the type described, a pair of power cylinders arranged in side by side relation,

a piston operable in said cylinders and dividing each into a compression chamber and a firing chamber, a fuel supply means, a single fuel inlet valve communicating with the fuel supply means, 5 said fuel inlet valve having direct communication with each of the compression chambers, each firing chamber being provided with an exhaust valve, each piston being formed with a fuel passage for effecting communication between its respective compression and firing chambers, a check valve associated with each piston for closing its passage to effect opening of said fuel intake valve to permit fuel to be drawn into the compression chamber upon movement of the piston in one direction and said check valve being operable to open the passage to permit fuel to be introduced into the firing chamber from the compression chamber upon movement of the piston in an opposite direction and to effect closing of said fuel intake valve, a single detonator cylinder having communication with each of said firing chambers, a detonator piston operable in said last cylinder for compressing fuel therein to ignite the 10 same, and means for operating said detonator piston. 5

FREDERICK P. GRAHMAN.
